(57) **CLAIM**

The ornamental design for a dish rack, as shown and described.

DESCRIPTION

The invention is a device for holding dishes, cutlery and utensils to allow water to drain out.

FIG. 1 is a front perspective view of the dish rack showing my new design;

FIG. 2 is a front elevation view thereof;

FIG. 3 is a rear elevation view thereof;

FIG. 4 is a right side elevation view thereof and it is the mirror image of a left side elevation view;

FIG. 5 is a top plan view thereof; and,

FIG. 6 is a bottom plan view thereof.
